UNITED STATES PATENT OFFICE.

JOHN H. DUNCAN, OF SYRACUSE, NEW YORK.

DRIER AND CONVEYER.

SPECIFICATION forming part of Letters Patent No. 423,598, dated March 18, 1890.

Application filed January 9, 1888. Serial No. 260,122. (No model.)

To all whom it may concern:

Be it known that I, JOHN H. DUNCAN, of Syracuse, in the county of Onondaga, in the State of New York, have invented new and 5 useful Improvements in Driers and Conveyers, of which the following, taken in connection with the accompanying drawing, is a full, clear, and exact description.

My invention relates to an improvement in 10 driers and conveyers; and it consists in certain peculiarities of the construction and arrangement of the same, substantially as will be hereinafter more fully described, and pointed out in the claims.

15 In order to enable others skilled in the art to which my invention pertains to make and use the same, I will now proceed to describe its construction and operation, referring to the accompanying drawing, in which the figure represents a longitudinal vertical section of my invention.

a represents a furnace or heater of any suitable size, form, and construction, provided with the usual grate-bars a' and bridge-wall a². No detailed description of this furnace is needed further than that here given, as its details are not material, and many such are well known and entirely suitable to use in connection with this apparatus.

30 Within the furnace-shell I place a coil of pipe b, having its lower end connected to a fan or blower b', and to this blower is also connected a pipe b², leading from a heating-chamber c, in which is a steam-coil c', properly connected to any suitable steam-generator, and an air-supply c² is also connected to this chamber. The upper end of the heating-coil b is connected to the pipe d, which is extended to enter the storage-room d', as shown. An 35 auxiliary pipe m, preferably of smaller diameter than the main one, is extended from the blower b', and is connected to the pipe d at a point just beyond its connection with the main blast-pipe b, as seen in the drawing, and

40 while the angle of connection of the pipes m and d will vary, as may be required in particular cases, I prefer to make this connection at an acute angle, in order that the blast from the auxiliary pipe shall need as little deflection as possible on joining the main current. Over this auxiliary pipe is placed a hopper e, into which the material to be operated upon

is run by a pipe e' from any room or storage-receptacle above. A connection f, between the hopper and the auxiliary pipe m, serves 55 to admit the passage of the material, and in this connection I place a spiral conveyer-screw f', the shaft of which extends out in any convenient position and is provided with a driving-pulley g or similar device, by which 60 the shaft may be connected to any suitable motive power. This device is intended for use in conveying any damp material (such as salt) from a receptacle in which it is stored, to what is usually termed the "dry-room," and 65 to dry the material thoroughly while in transit, and the operation will be readily comprehended from the preceding description. Air is drawn through the heating-chamber c by the influence of the fan or blower, and is partially 70 heated by contact with the steam-coil in said chamber. From the blower the main portion of the air is forced through the coil b in the furnace, and as the coil is in constant contact with the flames and products of combustion the air is 75 heated to an intense degree during its passage and enters the pipe d at an exceedingly high temperature. A portion of the air from the blower at the same time passes through the auxiliary pipe m, and also is forced into and 80 through the pipe d. The material to be dried and conveyed falling into the hopper is fed positively and evenly into the auxiliary blast-pipe m by the conveyer-screw f', which not only feeds the material in a steady stream, 85 but also effectually prevents any choking of the connection f by the damp material. As soon as the material enters the pipe m, it is caught by the auxiliary blast and carried forward into the pipe d, where the highly-heated 90 main blast at once carries it onward to the proper point of deposit, and during its passage it is thoroughly dried by the heat of the blast to which it is subjected. The employment of the auxiliary blast into which the 95 material is first fed and its connection with the main blast at an acute angle effectually overcomes the liability to clogging at this point, which has heretofore been an annoyance in such machines, and it will be noted 100 also that I provide the pipe-sections at this point with one or more removable portions n n, by means of which the interior of the pipes may be accessible at any time without trouble

and any incrustations and other obstructions removed.

It will be evident that the quantity of material handled may be readily regulated by varying the speed of the feeding-screw f' , so as to feed the damp material faster or slower, as desirable in its proper treatment.

The apparatus herein shown is well adapted to the carrying out of my invention; but I do not desire to confine myself to this peculiar construction, as it is evident that it may be changed in many details without in any manner departing from the spirit of my invention.

Having thus fully described my invention, what I claim as new, and desire to secure by Letters Patent, is—

1. The combination, with a hopper for holding the material, and a conveyer-pipe connected thereto, into the side of which the material is fed from the hopper, of a hot-air-blast pipe connected to one end of the conveyer-pipe, whereby the material is both dried and carried away by the hot blast, substantially as and for the purpose set forth.

2. In a drier and conveyer, the combination, with a fan or blower, and a furnace or heating device, of a pipe-coil within the furnace connected at one end to the blower and at the other to a conveyer-pipe, and means, substantially as described, for positively feeding the material into the air-blast in the conveyer-pipe, substantially as and for the purpose set forth.

3. In a drier and conveyer, the combination, with a conveyer-pipe provided with a hot-blast-pipe connection at its rear end, of a hopper connected to the conveyer-pipe, and a screw-conveyer in said connection for feed-

ing the damp material regularly and preventing choking the connection, substantially as and for the purpose set forth.

4. The combination, with a conveyer-pipe provided with means for feeding the material operated on regularly thereto, of a furnace having a pipe-coil arranged therein and connected at one end to the conveyer-pipe, and a blower connected to the other end, and an auxiliary heating-chamber provided with a steam-coil, through which air is drawn to the blower, substantially as and for the purpose set forth.

5. In a drier and conveyer, the combination, with a conveyer-pipe having a hot-air blast connected thereto, of an auxiliary blast-pipe connected to the conveyer-pipe at an acute angle, and a hopper for feeding the material to be acted upon connected to the auxiliary blast-pipe, substantially as and for the purpose set forth.

6. In a drier and conveyer, the combination, with a conveyer-pipe, and a hot-blast coil passed through a furnace for heating the air, of a blower connected thereto, an auxiliary heating-chamber from which the air is drawn to the blower, and an auxiliary blast-pipe connecting the blower with the conveyer-pipe, into which the material is fed, substantially as and for the purpose set forth.

In testimony whereof I have hereunto signed my name, in the presence of two attesting witnesses, at Syracuse, in the county of Onondaga, in the State of New York, this 30th day of November, 1887.

JOHN H. DUNCAN.
